COMBINED COSTUMER AND ACCESSORY HOLDER FOR A CHILD

Carol Guida, 423 S. 13th St., Philadelphia, Pa. 19147

Filed Jan. 16, 1974, Ser. No. 433,807

Term of patent 14 years

Int. Cl. D6—04

U.S. Cl. D6—20

FIG. 1

FIG. 2

FIG. 3

FIG. 4

FIG. 1 is a perspective view of the front of a combined costumer and accessory holder for a child in accordance with a preferred embodiment of my invention, showing part of the left side.

FIG. 2 is a perspective view of the front of the said preferred embodiment, showing part of the right side.

FIG. 3 is a view of the said embodiment taken from the rear.

FIG. 4 is a view of the said embodiment taken from the bottom thereof.

FIG. 5 is a side view of the said embodiment.

I claim:

The ornamental design for a combined costumer and accessory holder for a child, as shown.
